[57] CLAIM

The ornamental design for an automobile instrument panel,
as shown and described.

DESCRIPTION

FIG. 1 is a front view of an automobile instrument panel
constructed according to our novel design;

FIG. 2 is a fragmented top front and left side perspective
view of FIG. 1 the undisclosed right side of the panel is a
mirror image of the left side; and,

FIG. 3 is an enlarged fragmented front view of a center
section of FIG. 1.

Those portions of the drawing figures shown in broken lines
depict environment and are not to be considered part of the
novel design being claimed.
